UNITED STATES PATENT OFFICE.

JOHN W. HYATT, OF NEWARK, NEW JERSEY.

POLISHING-WHEEL.

No. 895,641.

Specification of Letters Patent.

Patented Aug. 11, 1908.

Application filed April 17, 1907. Serial No. 368,629.

To all whom it may concern:

Be it known that I, JOHN W. HYATT, a citizen of the United States, of 141 Commerce street, Newark, county of Essex, and State of New Jersey, have invented certain new and useful Improvements in Polishing-Wheels, fully described and represented in the following specification, and the accompanying drawings, forming a part of the same.

- 10 The object of the invention is to reduce the cost and improve the quality of that class of wheel-bodies upon which abrading material is cemented to be used in polishing and grinding. Such wheel-bodies have been
15 made of wood, leather, and other substances, but none of them is capable of preserving the form of the wheel perfectly, as wood shrinks unevenly, and the texture of leather is affected by heat or moisture.
20 The wheel-body in the present invention is formed of a yielding fibrous substance, as jute or hair felt, saturated with so-called printers' "roller-composition", which is made of glue and glycerin and which has the property of "setting" or hardening to a certain point and thereafter retaining a soft yielding character and permanent elasticity.

The composition can, without losing its yielding character, be made readily heat-resistant and water-resistant by the admixture of formaldehyde.

Hair felt of cheap or coarse grade is preferable, as it is very cheap, and when saturated with the printers' "roller-composition" and 35 the composition hardened to its normal point, it possesses a perfectly elastic yielding surface which is of the very best character for supporting the abrading material in a grinding or polishing operation.

40 In such an operation, it is desirable that the abrading material should be supported elastically, that it may operate uniformly upon various uneven convex and concave surfaces which require to be polished, and 45 the wheel-body thus constructed possesses such permanent yielding surface, and a very homogeneous consistency.

The animal or vegetable fiber when disposed irregularly, as in a felt or mat, imparts 50 strength to the wheel-body which resists the centrifugal force to a certain point, and the wheel-body may be made of a single disk, or of a series of disks cemented together, but where a high speed wheel is desired, it may 55 be formed of a series of disks cemented together with intermediate layers of woven

fabric, such layers serving to increase the strength of the wheel and resist the centrifugal force. As the printers' "roller-composition" contains glue, it can be used as a 60 cement; and a perfectly homogeneous quality thus secured in the binding material.

The invention will be understood by reference to the annexed drawing, in which

Figure 1 is a side view, and Fig. 2 an edge 65 view of a disk embodying the invention; and Fig. 3 is a transverse section of a wheel comprising a series of such disks with intermediate canvas layers, and a flanged hub secured in the disks. Fig. 4 is a side view of 70 the wheel-hub.

In the manufacture of the disks, hair felt, such as is used for boiler felting, is cut into circular sheets of the desired size and placed in a heated mold containing a fresh fluid 75 mixture of glue, glycerin and water, of suitable proportions to form a stiff jelly when cold, the quantity of mixture being sufficient to saturate the felt. A cover is placed upon the mold and slowly pressed to reduce the 80 saturated felt to a suitable thickness, in most cases about one-third of its original thickness. The pressure is graduated to produce the density of texture required for the grade of grinding material to be carried and the 85 nature of the work for which the wheel is intended. A lighter pressure is used where a disk of softer or more spongy texture is desired, and a heavier pressure producing a more firm and solid texture, such variations 90 in the body of the wheel being desired for different kinds of grinding work.

Where the disk is to be used alone, as represented at *a* in Fig. 2, a hole *b* of suitable size is formed in the center, as shown in Fig. 1, 95 for securing it upon a spindle, and the disk is pressed hard enough to give it the strength requisite to prevent bursting when rotated.

If a wheel of considerable thickness, as several inches, is required, then a series of 100 the disks is formed as just described, of sufficient number to make the wheel, and the disks are then cemented together and to intermediate layers of canvas *c* by the same fluid composition, with the iron hub *d* in the 105 center having a thin star-shaped or toothed flange *e* to firmly engage the center disks of the wheel.

The group of disks with their hub is firmly 110 pressed together and upon such flange, and baked at a temperature of about two hundred degrees for several hours. Such baking

dissipates a portion of the water from the composition and may be graduated to give the wheel any desired degree of hardness in its texture. The wheel is then mounted 5 upon a mandrel and turned after which it is ready to receive the abrasive material which would be glued upon the wheel in the same manner as on other wheel-bodies. Wheel-bodies for such a purpose have heretofore 10 been made of leather of various kinds which involves a very great expense, or of wood which does not remain truly circular, and the present invention furnishes a wheel-body which is superior in quality to either of these 15 materials as it is homogeneous in texture, and possesses when properly made a slight yielding quality which is of great value in supporting and operating the abrasive material.

The wheel-body furnishes a new article of 20 manufacture which may be made up in assortments of dimensions ready for use by grinders and polishers in many different arts.

Having thus set forth the nature of the invention what is claimed herein is:

- 25 1. A polishing wheel comprising yielding hair felt saturated and cemented together with printers' "roller-composition" of permanently yielding character.
2. A polishing wheel comprising a yielding 30 fibrous material saturated and cemented together with printers' "roller-composition" of permanently yielding character and rendered

heat-resistant and water-resistant by the admixture of formaldehyde.

3. A polishing wheel comprising a series of 35 disks formed of a yielding hair felt material saturated with printers' "roller-composition" of permanently yielding character rendered heat resistant and water resistant by the admixture of formaldehyde, the disks being 40 cemented together with alternate layers of woven fabric by a cement of "roller-composition," the layers of woven fabric serving to resist the centrifugal force developed in rotating the wheel.

4. A polishing wheel comprising a central hub with a toothed flange intermediate to its ends, disks of compressed hair felt applied to the hub at opposite sides of such flange and pressed thereon and cemented together by 50 permanently yielding printers' "roller-composition", the pores of the disks being also filled with the printers' "roller-composition" of permanently yielding character rendered heat-resistant and water-resistant by the ad- 55 mixture of formaldehyde.

In testimony whereof I have hereunto set my hand in the presence of two subscribing witnesses.

JOHN W. HYATT.
